No. 36,954.

Patented June 7, 1904.

UNITED STATES PATENT OFFICE.

FREDA LOVE PERKINS, OF DENVER, COLORADO.

DESIGN FOR A CANDLE-HOLDER FAVOR.

SPECIFICATION forming part of Design No. 36,954, dated June 7, 1904.

Application filed May 2, 1904. Serial No. 206,074. Term of patent 3½ years.

To all whom it may concern:

Be it known that I, FREDA LOVE PERKINS, a citizen of the United States of America, residing in the city and county of Denver and State of Colorado, have invented a new, original, and ornamental Design for Candle-Holder Favors, reference being had to the accompanying drawings, which form a part of this specification.

This invention relates to a new, original, and ornamental design for a candle-holder favor, the said design being illustrated in the accompanying drawings, in which—

15

What I claim is—

The ornamental design for a candle-holder favor as shown in the drawings.

FREDA LOVE PERKINS.
